UNITED STATES PATENT OFFICE.

THOMAS W. DIXON, OF ST. LOUIS, MISSOURI, ASSIGNOR OF ONE-HALF TO WILBUR H. WHITE, OF ST. LOUIS, MISSOURI.

VENTILATED FIXTURE.

1,149,560.

Specification of Letters Patent. Patented Aug. 10, 1915.

Application filed April 19, 1915. Serial No. 22,394.

To all whom it may concern:

Be it known that I, THOMAS W. DIXON, a citizen of the United States, and residing at the city of St. Louis and State of Missouri, have invented a new and useful Ventilated Fixture, of which the following is a specification.

This invention relates to ventilated fixtures for electric lamps, and it consists of the novel construction, combination and arrangement of parts and features hereinafter shown, described and claimed.

My improved fixture consists of a socket supporting member having a shield or protector in connection with the lower portion thereof, a globe support supported below and protected by the shield or protector and provided with ventilation openings whereby hot air from the globe or lamp is released from around the upper portion of the lamp, and novel supporting devices for supporting the globe support below the shield or protector so as to leave a relatively large open space for the passage of the air between the protector shield and the globe support so that the cooling atmosphere may freely circulate between said parts and from the globe and its support.

Embodying the above and many other improved features of construction and arrangement, my invention attains many desirable objects and results, all of which will be made apparent to those skilled in the art to which this invention relates by the following detail description wherein reference is made to the accompanying drawings in which—

Figure 1 is a side elevation of a ventilated fixture constructed in accordance with my invention. Fig. 2 is a similar view with the socket support and the protecting shield in section in order to illustrate the relative arrangement and position of said parts with respect to the globe support. Fig. 3 is an inverted view of the fixture. Fig. 4 is a plan view of the globe support, the connecting devices whereby said support is connected to the socket support and shield being in section. Fig. 5 is a vertical sectional view of the entire fixture, the socket being removed from the support.

As illustrated in the accompanying drawings the preferred embodiment of my invention includes a tubular socket support 1

the lower end of which is open for the insertion of the socket, and the upper end of which is provided with a threaded opening whereby the fixture may be connected to a supporting pipe 2 in which are inclosed the wires 3 which lead to the two usual contact members in the lamp socket 4. The socket 4 may be of any usual or preferred construction and is received in the tubular support 1, being attached thereto by screws 5 which pass through holes in the end wall 6 of the socket, through heat non-conducting blocks 5^a, and engage in threaded holes in bosses 6 integral with the upper end of the support 1. As usual the socket 4 is of suitable non-conducting material so that the metallic parts of the fixture are insulated from the wires. The lamp may be connected to the socket by the usual threaded connection (not shown). The blocks 5^a support the socket 4 away from the end of the member 1, thus providing a space for the circulation of air entirely around the socket.

The lower end of the support 1 is provided with a circumferential flange 7 at its lower end from which extend a number of lateral projections 8. A shield, preferably composed of sheet metal in the form of a disk, is supported at the lower end of the member 1. The shield preferably includes a flat portion 9 bearing against the flange 7 and the projections 8 and provided with a central opening through which the socket 4 extends and an obliquely disposed portion 11 substantially in the form of a truncated cone of which the flat portion 9 forms the upper end. Below the shield 9—11 the globe support is secured, said support comprising an annular portion 12 from which rises an oblique or conical portion 13 above which extends an annular portion 14 bent to provide an internal flange 15. The flange 15 is immediately below the flat portion 9 of the shield, and also below the extensions 8. Supporting members 16 pass through the extensions 8 and the flat portion 9 of the shield, and through spacing members 17 placed between the flange 15 and the flat portion 9. The supporting members also pass through the flange 15 and have releasable nuts 18 screwed on the lower ends thereof and clamping the flange 15 against the members 17 and supporting all of the elements in rigid connection with the socket

support 1. The members 17 are preferably of non-conducting material so that the heat from the globe support will not be thereby conducted to the upper metallic parts of the fixture. The members 17 support the parts so as to form an open space 19 around the lamp socket for the free circulation of the air, so that the cooling atmosphere may prevent the parts from becoming heated to an excessive extent.

The rising portion 14 of the shade support is provided with numerous holes 20, and the flange 15 is also provided with numerous holes 21, all of which constitute passages for the circulation of the air into and out of the globe. It will be observed that these air circulating passages are adjacent to the socket, the point of maximum heat of the lamp, so that the cooling currents of air are constantly applied where they are most needed.

The shield 9—11 above the passages constitutes a guard to prevent entrance of foreign substances and insects, since the lower edge of the shield is in a plane substantially below the large passage 19. Obviously, the shield may be extended to any desired extent, so that the principle of the invention includes a device or guard for thoroughly protecting the ventilation openings.

The annular part 12 of the shade support is provided with threaded bearings 22^a in which the screws 22 are operatively mounted in annular series so that said screws may be manipulated to engage the globe 23 and support the same in connection with the fixture. The screws are provided with manually engageable heads or knobs whereby they may be readily engaged with or released from the globe in the well understood manner.

By the construction illustrated and described the globe 23 and the lamp socket and also the lamp have free communication with the open atmosphere. The provision of the holes 20 and 21 in different planes, and the open space 19 above the shade supporting member permit the heated air to pass from the fixture, and cooling currents of air to come into contact with the heated parts of the fixture at all times. In this way excessive heating of the fixture is obviated. The shield which is supported above the ventilation openings also serves as a protector to prevent rain and snow and other elements from entering the ventilation openings. The oblique portion of the shield causes the objects and elements falling thereon to drop below the plane of the ventilation openings, and the portion 13 of the globe support deflects the objects or elements away from the open end of the globe.

It will be understood that there may be minor variations in the construction and ar-

rangement of the parts comprising the invention without departing from the principles herein disclosed.

What I claim and desire to secure by Letters Patent of the United States is:

1. A fixture comprising a socket supporting member, a globe support, a shield, spacers between said shield and said globe support forming a space for the passage of air below said shield into said globe support, and devices passing through said spacers and said shield and said globe support and engaging said socket supporting member effectively to hold said parts in the adjustment aforesaid.

2. A fixture comprising a socket supporting member, a shield having oblique upper surfaces supported at the lower end of said socket supporting member, a globe support below said shield and having passages therethrough, bolts supporting said shield and said globe support from said socket supporting member, and spacers interposed between said shield and said globe support for holding said parts in spaced adjustment to enable air to pass into said globe support.

3. A device of the character described, comprising a socket supporting member, a socket supported by and extending below said member, a shield at the lower end of said member, a globe support below said shield, means for supporting said globe support and said shield by said supporting member, spacers interposed between said shield and said globe support, passages between said shield and said globe support around said socket, and means for supporting a globe from said globe support.

4. A device of the character described, comprising a socket supporting member, a socket supported by said member, a shield below said member, a globe support, means for supporting said shield and said globe support from said supporting member, spacers interposed between said shield and said globe support and forming passages between said shield and said globe support around said socket, passages through said globe support below said first-named passages, and screws for supporting a globe in connection with said globe support.

5. A ventilated electric light fixture, comprising a hollow member adapted to receive the socket, a lamp socket within said hollow member, non-conducting elements between said socket and said member, there being an open space between said socket and said member on all sides of said socket, a shield supported below said member, a globe support below said shield, and air passages through said globe support and between said globe support and said shield communicating with the space around said socket.

6. A ventilated fixture for electric lights, comprising a hollow support, a socket with-

in said support, non-conducting elements holding said socket out of contact with said support, there being an open space on all sides of said socket within said support, a globe supports below said first-named support, passages through said globe support communicating with the open space around said socket, and a shield above said globe support below said first-named support ex-
tending obliquely downwardly and out-

wardly in a direction away from said passages.

In witness whereof I have signed this specification in the presence of two subscribing witnesses.

THOMAS W. DIXON.
